MOTOR STOP-START ARRANGEMENT FOR
TELEGRAPH RECEIVERS

Thomas Geoffrey Poulter, Chelmsford, England,
assignor to Marconi's Wireless Telegraph Company Limited, London, England, a company of Great Britain

Application July 8, 1948, Serial No. 37,643
In Great Britain July 31, 1947

4 Claims. (Cl. 178—4.1)

1

This invention relates to motor stop-start arrangements for printing telegraph and like receivers and more particularly to such arrangements of the kind in which the usual printing telegraph receiver motor is provided with a control circuit whereby it may be stopped or started by suitable telegraph signals transmitted from the co-operating transmitter.

The invention is illustrated in and explained in connection with the accompanying drawings in which Fig. 1 is a diagrammatic figure, provided for explanatory purposes, illustrating a known arrangement, and Fig. 2 is a diagrammatic figure illustrating an embodiment of the present invention.

In order that the invention may be the better understood a known motor stop-start arrangement of the kind referred to will first be described together with the defects which the present invention seeks to avoid. In this known arrangement, illustrated in Fig. 1, the armature 2 of the printing telegraph receiver relay, whose winding 1 is connected to the receiving set (not shown) is provided with back contacts 3 in parallel with the winding 4 of a first control relay whose armature has an end slug which delays its operation, on energization, by about 50 milli-seconds and its release, on de-energization, by about 100 milliseconds. Such slugged relays are well-known per se in the electric control, telegraph and automatic telephone arts and are therefore deemed to require no detailed description herein. One example of such relay is illustrated for example in C. P. Clare Patent 2,355,055, dated August 8, 1944. The said back contacts are normally closed, i. e. are closed when the telegraph relay is on space and open when it is on mark. The winding 4 of the said first control relay is connected through a limiting resistance 5 across a battery or other source (not shown but represented by its positive and negative terminals + and —) and when energized, closes (after the delay stated) normally open contacts 6 which are in series with the closing coil 7a of a two-coil relay. This series circuit, which extends from the battery or other source, also includes the normally closed contacts 12 of a bi-metallic thermal or other delay relay as well known per se the heating winding 11 of which is also connected to the source through the normally open contacts 6 of the first control relay, when energized. The two-coil relay has two pairs 8, 9 of normally open contacts one pair 9 of which, when closed completes the circuit of the motor 10 and the other pair 8 of which, when closed connects the second or locking coil 7b of

the relay in question to the said source, this circuit also including the thermal relay contacts 12.

With this arrangement a prolonged mark signal of about $\frac{1}{2}$ to 1 second starts the motor 10 by closing the contacts 6 of the first control relay which in turn energizes the two-coil relay (which locks itself in) to complete the motor circuit. A longer mark of about 10 seconds duration stops the motor by first causing energization of the first control relay and then causing the thermal relay to open its contacts 12 and thus break the circuits of both windings 7a, 7b of the two-coil relay.

This circuit has two main disadvantages. If the transmitter operator sends a stop signal appreciably longer than the ten seconds necessary to operate the thermal relay, the bi-metallic element of this relay becomes much overheated and takes about 2 minutes to restore instead of the usual 20 to 30 seconds. Until this relay restores it is not possible to restart the motor by the start signal, which often comes about $\frac{1}{2}$ minute after the stop signal. Secondly the "slugged" first control relay is not immune from operation by noise, especially in a period when no message is being sent. If the said relay operates on noise the motor starts and blank tape is fed from the telegraph receiver. Further the said relay is apt to operate frequently during reception of a message, causing pulses of current to flow through the heating winding of the thermal relay. These pulses may, if they are long enough and close enough together, cause the thermal relay to open its contacts 12 and thus stop the motor. If the thermal relay operates in this way it may remain operated for a long period necessitating resort to a manual stop-start switch. For these reasons the known system described is not reliable enough to be left without supervision. The present invention seeks to avoid these defects.

According to this invention a printing telegraph or like receiver motor start-stop arrangement of the kind referred to comprises a first control relay whose winding is connected in circuit so as to be energized when the normally provided telegraph receiver is on space, delay means associated with said relay to delay its release after said circuit is broken, a motor control relay having an operating winding connected to be energized on release of said first control relay and adapted on energization, to complete the motor circuit, a maintaining circuit adapted to be closed on energization of said operating winding and to maintain the motor circuit completed after said operating winding has been energized, and a ther-

mal or other delay relay having a winding connected to be energized on energization of the first control relay and having contacts adapted, on operation of said delay relay to break said operating winding and said maintaining circuits.

Preferably the delay means associated with the first control relay are constituted simply by a condenser in parallel with its winding.

In a preferred embodiment illustrated in Fig. 2 the winding 21 of the normally provided telegraph relay operates by its armature 22 back contacts 23 which, when the relay is on space, energizes the winding 24 of a first control relay having a pair of normally closed contacts 26. This winding has a condenser 13 in parallel therewith whereby, when the back contacts 23 open, the charge on the condenser delays release of the first control relay by about 250 milliseconds. The normally closed contacts 26 complete the energizing circuit of one winding 21a of a two-coil relay, said circuit also including, in series, the normally closed contacts 212 of a thermal or other delay relay of any convenient well known construction having a delay of about 5 to 7 seconds. The two-coil relay has a second, or maintaining, winding 27b the circuit of which is completed by contacts 28 which the said relay itself closes when actuated, said relay also having normally open contacts 29 which, when closed, complete the circuit of the motor 10. The heater winding 211 of the thermal relay is in series with both the normally closed contacts 26 of the first control relay and with the contacts 212 of the said thermal relay itself, the last mentioned contacts also being in the circuits of both coils 27a, 27b of the two-coil relay.

With this arrangement the transmission of a mark of substantially more than 250 milliseconds duration causes release of the first control relay, operation and locking-in of the two-coil relay and starting of the motor. Thereafter transmission of a mark exceeding the thermal relay delay e. g. a mark of 10 seconds—causes the thermal relay to open its contacts 212 tripping out the two-coil relay and stopping the motor. Since the heater circuit is broken immediately the thermal relay contacts open, the heater begins to cool immediately, however long the mark to stop the motor may be. After a further 20 seconds the thermal relay contacts 212, which have a toggle action, in the ordinary well known way return to their original position and the arrangement is ready for another start signal.

The main advantages of the above described circuit are:

(a) Since noise cannot cause the motor to start, the receiver will not feed out tape during idle periods.

(b) Since normal signals do not operate the control circuit, the receiver will not stop during reception of traffic.

(c) The receiver is always ready to receive a start signal within about 20 seconds of the end of a stop signal irrespective of the length of the stop signal.

(d) Because of its immunity from operation by noise, the apparatus may be used on any circuit which is good enough to give legible printing, whether by line or by wireless.

It is found that the improved reliability is such that an apparatus as above described can be safely left unattended—a great advantage.

What I claim is:

1. In a printing telegraph or like receiver motor stop-start arrangement wherein the print-

ing telegraph receiver motor is provided with a control circuit which stops and starts said motor under the control of telegraph signals transmitted thereto from a co-operating transmitter, the combination of a first control relay having a winding, means connecting said winding in circuit so as to energize the same when the normally provided telegraph receiver is on space, delay means associated with said relay to delay its release after said circuit is broken, a motor control relay having an operating winding, means connecting said operating winding to energize the same on release of said first control relay, means, actuated on energization of said operating winding, for completing the motor circuit, a maintaining circuit connected to be closed on energization of said operating winding for maintaining the motor circuit completed after said operating winding has been energized, and a delay relay having a winding connected to be energized on energization of the first control relay and having contacts connected to break said maintaining circuit and also the circuits of said last mentioned winding and of said operating winding on operation of said delay relay.

2. In a printing telegraph or like receiver motor stop-start arrangement wherein the printing telegraph receiver motor is provided with a control circuit which stops and starts said motor under the control of telegraph signals transmitted thereto from a co-operating transmitter, the combination of a first control relay having a winding, means connecting said winding in circuit so as to energize the same when the normally provided telegraph receiver is on space, delay means associated with said relay to delay its release after said circuit is broken, a motor control relay having an operating winding, means connecting said operating winding to energize the same on release of said first control relay, means, actuated on energization of said operating winding, for completing the motor circuit, a maintaining circuit connected to be closed on energization of said operating winding for maintaining the motor circuit completed after said operating winding has been energized, and a thermal delay relay having a winding connected to be energized on energization of the first control relay and having contacts connected to break said maintaining circuit and also the circuits of said last mentioned winding and said operating winding on operation of said delay relay.

3. In a printing telegraph or like receiver motor stop-start arrangement wherein the printing telegraph receiver motor is provided with a control circuit which stops and starts said motor under the control of telegraph signals transmitted thereto from a co-operating transmitter, the combination of a first control relay having a winding, means connecting said winding in circuit so as to energize the same when the normally provided telegraph receiver is on space, delay means comprising a condenser in parallel with the winding said relay to delay its release after said circuit is broken, a motor control relay having an operating winding, means connecting said operating winding to energize the same on release of said first control relay, means actuated on energization of said operating winding, for completing the motor circuit, a maintaining circuit connected to be closed on energization of said operating winding for maintaining the motor circuit completed after said operating winding has been energized, and a delay relay having a winding

connected to be energized on energization of the first control relay and having contacts connected to break said maintaining circuit and also the circuits of said last mentioned winding of said operating winding on operation of said delay relay.

4. In a printing telegraph or like receiver motor stop-start arrangement wherein the printing telegraph receiver motor is provided with a control circuit which stops and starts said motor under the control of telegraph signals transmitted thereto from a co-operating transmitter, the combination of a first control relay having a winding, means connecting said winding in circuit so as to energize the same when the normally provided telegraph receiver is on space, delay means comprising a condenser in parallel with the winding said relay to delay its release after said circuit is broken, a motor control relay having an operating winding, means connecting said operating winding to energize the same on release of said first control relay, means, actuated on energization of said operating winding, for completing the motor circuit, a maintaining circuit

connected to be closed on energization of said operating winding for maintaining the motor circuit completed after said operating winding has been energized, and a thermal delay relay having a winding connected to be energized on energization of the first control relay and having contacts connected to break said maintaining circuit and also the circuits of said last mentioned winding and said operating winding on operation of said delay relay.
